STRIPPING MACHINE

Stanley S. Millen, Glendale, Calif., assignor to
Julius Schmid, Los Angeles, Calif.

Application November 7, 1935, Serial No. 48,722

10 Claims.

(Cl. 18—2)

The present invention relates to means to strip thin rubber articles such as finger cots, toy balloons, etc., from forms on which said articles have been processed by the means shown, and 5 after the manner described in my copending application for patent, entitled Bead forming machines, application No. 44,555 filed October 11, 1935.

The device of this invention forms a unit or 10 step in a series of operations, some of which are precedent to, and others of which are subsequent to the function of the present invention.

In the manufacture of such devices as finger cots, toy balloons, etc., it is customary to dip 15 forms or patterns 20 into a bath of liquid rubber in a vat as indicated by reference character 23, Figure 1, and by one or more dippings build up an accumulation of rubber on the forms 20 until the coating on the forms is sufficiently heavy 20 to conform with the duty to be imposed on the article.

Form boards 21 are adapted to support forms 20 in pendant position and are adapted to roll over the over head track 22 from stations A to 25 B—C—D—E and F, and after sufficient dipping at station A, is moved via the over head track 22 to station B where the articles formed are dried. After drying, the forms are moved to station C, where the articles formed on form 20 are beaded 30 or ringed in a machine 24 as described in my copending application for patent, entitled Bead forming machines, above referred to.

After being processed at station C, the forms are moved to station D for vulcanizing in vulcanizer 25. The forms are then moved to station E to a machine 30 for stripping, which operation forms the basis of the present invention. Subsequent to the stripping operation, the forms are cleansed at station F in a cleansing machine 27, prior to being returned to the point of beginning 40 for repetition of the cycle of operation just described.

The aforementioned stations, as illustrated in 45 Figure 1, are schematic only and form no part of the present invention, which is concerned only with means to remove the articles after formation and processing.

It is therefore a prime object of the present 50 invention to provide an automatic machine which will simultaneously strip a plurality of formed articles from the forms on which said articles have been builded and processed.

Another object of the invention is to provide 55 means to deliver the aforementioned forms to a

machine wherein the articles builded on said forms may be automatically removed therefrom.

A further object of the invention is to provide means to automatically remove the aforementioned forms from the stripping machine, after 5 the articles builded thereon have been stripped from the forms.

A still further object of the invention is to provide a machine that will remove thin rubber articles, from forms, more economically, more uniformly, and with greater rapidity than has heretofore been possible.

Referring to the drawings, of which there are five sheets:

Figure 1 is a schematic view, showing the several stations at which operations, precedent and/or subsequent to the operation with which the machine of this invention is concerned, take place.

Figure 2 is a side elevation, although partly in section, showing construction.

Figure 3 is a sectional elevation, showing construction in detail.

Figure 4 is a plan view, taken on line 4—4, Figure 2.

Figure 5 is a detail of one of the spreader units 25 for the stripping brushes.

Figure 6 is a detail, taken on line 6—6, Figure 5.

Figure 7 is a sectional elevation, taken on line 30 7—7, Figure 3.

In the drawings, the machine of this invention is represented by the reference character 30.

A table 32 having a top 34, resting upon legs 36, forms the base for supports 38, upon which 35 stripping units 40 are operably mounted.

As shown, particularly in Figures 2, 5, and 6, the stripping units 40, comprise a vertically movable cam rod 42, operating through bearings 44 and 46. The upper end of the cam rod 42 is 40 provided with a fitting 48 to which laterally extending arms 50 are pivoted as shown at 52. Worm gears 54 are secured to transversally extending stripper brush shafts 56 and are revolvably connected to the ends 58 of arms 50. The 45 supports 38 are provided with slots 60 through which shafts 56 may be urged in a manner to be hereinafter described.

The ends of shafts 56 are enlarged, as by a bushing 64 so as to occupy the full depth of the 50 slots 60 to prevent shaft chatter during rotation of shafts 56, and collars 62 prevent drift and consequent misalignment of shafts 56, gears 54 and stripper brushes 56 during rotation of the shafts.

A horizontally disposed shaft 70, journaled in 55

bearing 72, is adapted to drive worm gears 74, which are in mesh with gears 54 and which drive gears 54 to rotate brush shaft 56. A pulley 76 is mounted on shaft 70 and is operably connected with an electric motor 78 through belt 80. A base 82, is adapted to support the motor 78 and a speed reduction device 84. A shaft 86, extending from the device 84, is provided with a pulley 88, which is operably connected to a cam 10 shaft 90' by means of a pulley 92 and a belt 94. The cam shaft 90' is journaled in bearings 96 and is provided with a plurality of cams 98 adapted to lift cam rods 42.

As shown in Figures 3 and 4, the ends of brush shafts 56 are each provided with lateral spreading arms 50 and cam rods 42 to actuate the arms 50. For the sake of convenience, I will designate the spreading means as groups A and B.

Group A includes means to rotate shafts 56 as well as means to spread said shafts; whereas group B only includes means to spread shafts 56 in cooperation with group A.

In order to operate group B of the spreading means, I place sprocket wheels 93 on cam shafts 90' and 90 over which a chain 91 is adapted to run, thereby tying the movements of cam shafts 90' and 90 into unison and ensuring that cam rods 42 and lateral arms 50 will move synchronously to spread shafts 56.

30 An extensile spring 100 encircles the cam rod 42, one end of the spring rests upon plate 102 held in position by a keeper 104, while the opposite end of the spring abuts the lower end 106 of bearing 44.

35 The foregoing construction ensures that the cam rod 42 will return to its lower position after the lobe 108, of cam 98, passes from under the lower end of cam rod 42.

A cam 112, is mounted upon cam shaft 90' and 40 revolves therewith, to operate lever 114, by reason of a cam-way following pin 116, which follows through the cam-way 118 as cam 112 revolves with shaft 90'.

45 Lever 114 is oscillatably mounted upon a bracket 120 and is provided with an extension 122 to which is fitted a throw rod 124. The rod 124 is connected to leg 126 of a bell crank 128, resting upon a base 127, the leg 130 of bell crank 128 is fitted with a throw rod 132.

50 Rod 132 is adjustably secured to bell crank 134, which is connected to bell crank 136 by means of an adjustable link 138. Bell crank 136 operates a fluid pressure valve 140 on power cylinder 142 by means of a control arm 144 and link 55 146.

An inlet pipe 148, admits fluid, preferably oil, under pressure to cylinder 142 to move piston rod 150 upwardly or downwardly in conformity with the setting of the valve 140 and its timed operation from cam 112. An exhaust pipe 152 permits the discharge of worked fluid from the cylinder 142.

55 The piston rod 150 is provided at its work end with a structure 154 which is adapted to hold 60 over head rail sections 156 in spaced alignment with the over head system 22, and to move said sections 156 vertically with respect to the medial vertical center of said power cylinder 142 and said piston 150.

70 Figure 3 clearly shows the manner in which form boards 21 are suspended upon rollers 158 and intermediate supporting devices 160.

75 By referring to Figure 4, it will be observed that stripping brushes 66 are positioned on shafts 56 at spaced intervals, and it will be noted that

the intervals correspond to the spaced intervals between the forms 20 on boards 21 so that the forms 20 will be in alignment with stripping brushes 66, when the forms 20 are lowered to a proper working level. It is quite essential that 5 brushes 66 and forms 20 be in alignment, and in order to effect such proper alignment I provide guide-ways 162 which are secured to a structural member 164 of frame 166 by means of bolts 168.

The guide-ways 162 are formed with slots 170 10 within which lugs 172, formed on the outer faces of rail sections 156, are adapted to move, thereby aligning section 156 with the overhead system 22 and with the medial vertical center of stripping brushes 66.

15 A centering pin 175 is adapted to fit within an aperture formed in the structure 154 and to pass through a matched aperture in alignment with said first mentioned aperture, said second mentioned aperture being formed in form boards 21, thereby aligning the movable boards 21 with respect to the structure 154 to prevent drift.

A hopper 177 is placed under the positions occupied by the forms 20 during the stripping operation and is adapted to receive the articles 179 25 as they are stripped from the forms 20, a drawer 181 is adapted to snugly fit within the hopper 177 to receive the articles 179 and forms a convenient means to remove the finished product from the stripping machine.

30 The operation of the machine is as follows:

The motor 78 is started by pressing button 192 thereby closing switch 193 to permit power to flow, from a source not shown, to the motor.

The motor 78 through pulley 79, belt 80, and 35 pulley 76 rotates shaft 70 and gears 74. Gears 54 in mesh with gears 74 are rotated, thereby rotating shafts 56 and stripping brushes 66. Gears 74 and 54 are so cut that the stripping brushes rotate inwardly, or toward one another.

40 Simultaneously with the above operation, the cam shafts 90' and 90 are driven through motor 78, speed reducing device 84, pulleys 88 and 92, and belt 94 to rotate cams 98, thereby lifting cam rods 42. As cam rods 42 are forced vertically, 45 through bearings 42 and 46, lateral arms 50 are forced divergently, thereby causing gears 54 to roll along the under side of gears 74, but simultaneously maintaining their operative relationship and forcing shafts 56 divergently.

50 Cam 112 rotating with cam shaft 90' and operating through pin 116, lever 114 and 122, rod 124, bell crank 128, rod 132, bell crank 134, link 138, bell crank 136, link 146, and valve control arm 144 admits fluid under pressure to 55 the upper end of power cylinder 142, thereby forcing piston 150 and structure 154 carrying a plurality of forms 20 downwardly. The downward movement of the forms 20 and the spreading of the brushes 66 are so timed that the forms 60 20 pass between the spreaded brushes 66, but at the moment the forms 20 reach their lower-most position the brushes 66 are caused to move convergently upon the forms, for the reason that the cam lobe 108 has passed from under cam rods 65 42, thereby permitting springs 100 to force rods 42 downwardly carrying lateral arms 50 with it and simultaneously rolling gears 54 along the under face of gears 74, thereby rolling shafts 56 and bushings 64 through slots 60 to effect frictional contact between brushes 66 and the articles 179 on forms 20.

70 At the moment forms 20 reach their lower-most position, cam 112 through the aforementioned linkage, reverses valve 140 and admits 75

fluid under pressure to power cylinder 142 to force piston 150 and structure 154 upwardly, thereby lifting forms 20 while they are being brushed by the rotating action of stripping brushes 66.

It has been found that when the forms 20 are lifted against the brushing action of brushes 66 that the sides of the articles 179 are rolled into a compact and neat annular ring, and that after 10 the lower end of forms 20 has passed through the brushes 66, that the rolled article 179 will drop into the hopper 177 and/or drawer 181 from which groups of articles 179 may be taken for testing and/or packaging.

15 The foregoing describes one cycle of operation. As soon as the piston 150 and structure 154 have lifted the overhead section 156 to a point in matched alignment with overhead section 22, pin 175 is removed, and form board 21 is rolled along 20 the overhead 22 to station F wherein the forms 20 are cleansed, which operation, of course, forms no part of the present invention.

Upon removal of the form board 21, a second form board 21' is rolled into section 156 and the 25 previously described cycle of operation is again repeated.

I claim:

1. In a machine to strip thin rubber articles from forms by frictional contact, laterally movable shafts provided with friction means, means to constantly rotate said shafts, and means to move said shafts from and into frictional contact with said forms, and elevator means to move 35 said forms and the articles on said forms, in vertical directions, against the direction of rotation of said shafts and said friction means.

2. In a machine to simultaneously strip a plurality of thin rubber articles from a group of forms by frictional contact, laterally movable 40 shafts provided with friction means, means to constantly rotate said shafts, means to move said shafts from and into frictional contact with said forms, and means operated in timed sequence to place said forms in position for frictional contact 45 with said friction means, and elevator means to move said forms and the articles on said forms, in vertical directions, against the direction of rotation of said shafts and said friction means.

3. In a machine to simultaneously strip a plurality of thin rubber articles from a group of forms by frictional contact, laterally movable shafts provided with friction means, means to constantly rotate said shafts, means to move said shafts from and into frictional contact with said forms, means operated in timed sequence to place 50 said forms in position for frictional contact with said friction means, and means operated in timed sequence to withdraw said forms from frictional contact with said friction means, and elevator means to move said forms and the articles on said forms, in vertical directions, against the direction of rotation of said shafts and said friction means.

4. In a machine to strip thin rubber articles from forms, said machine comprising a plurality of pairs of shafts having brushes, supports to journal said shafts, slots in said supports, cam rods for each of said pairs of shafts, said cam rods being operable at opposite ends of said shafts, a power shaft, gears on said power shaft, a gear on one end of each of said brush shafts, said first mentioned and said second mentioned gears being in operative engagement, links joining said cam rods and the ends of said brush shafts, and cams to operate said cam rods.

5. In a machine to simultaneously strip thin rubber articles from a group of forms, a plurality of stripping units, said units including rotating brushes, means to move said forms downwardly along the medial vertical axis of the inner working faces of said brushes, means to spread said brushes for placement of said forms, means to cause said brushes to rotate in engagement with said forms and said articles, and means to withdraw said forms along said medial vertical axis 10 from operative contact with said brushes. 5

6. In a machine to strip thin rubber articles from forms, a stripping unit, means to operatively support said stripping unit, vertically movable cam rods, cams to actuate said rods, laterally extending arms pivoted to said rods, transversely extending brush shafts, a plurality of brushes on said shafts, a power driven shaft, means to deliver rotational effort from said power shaft to said brush shafts, and means joining 20 said laterally extending arms to said brush shafts to transmit motion from said cam rods to said brush shafts. 15

7. In a machine to strip thin rubber articles from forms, a stripping unit, means to operatively support said stripping unit, vertically movable cam rods, cams to actuate said rods, laterally extending arms pivoted to said rods, transversely extending brush shafts, a plurality 30 of brushes on said shafts, a power shaft, gears on said power shaft, a gear on each of said brush shafts, said first mentioned gears being in operative engagement with said second mentioned gears, and means joining said brush shaft with said laterally extending arms to transmit motion 35 from said cam rods to said brush shafts. 25

8. In a machine to strip thin rubber articles from forms, a stripping unit, means to operatively support said stripping unit, vertically movable cam rods, laterally extending arms pivoted 40 to said rods, transversely extending brush shafts, a plurality of brushes on said shafts, a power shaft, gears on said power shaft, a gear on each of said brush shafts, said first mentioned gears being in operative engagement with said second 45 mentioned gear to rotate said second mentioned gear, said brush shaft being joined to said laterally extending arms whereby motion from said cam rods may be transmitted to said brush shafts, said unit supporting means being provided with 50 slots through which said brush shafts may move in response to pressure from said cam rods.

9. In a machine to strip thin rubber articles from forms, a stripping unit, means to operatively support said stripping unit, vertically movable cam rods, laterally extending arms pivoted to said rods, transversely extending brush shafts, a plurality of brushes on said shafts, a power shaft, gears on said power shaft, a gear on each 55 of said brush shafts, said first mentioned gears being in operative engagement with said second mentioned gear to rotate said second mentioned gear, said brush shaft being joined to said laterally extending arms whereby motion from said cam rods may be transmitted to said brush shafts, said unit supporting means being provided with 60 slots through which said brush shafts may move in response to pressure from said cam rods, and means to prevent shaft chatter during rotation 70 of said brush shafts. 65

10. In a machine to strip thin rubber articles from forms pendently supported on movable boards, said machine comprising a table, a plurality of stripping units, means to operatively 75

support said stripping units, said unit supporting means being provided with slots, a plurality of brush shafts extending transversally of said table and through said slots, a pair of brushes for each 5 of said forms, a gear on one end of said brush shafts, a power shaft, gears in said power shaft, said first mentioned gear being in operative engagement with said second mentioned gears, cam rods, cams to actuate said cam rods, laterally 10 extending arms, one end of said arms being pivoted to said cam rods, the opposite end of said

arms being engaged by said brush shafts, a motor, power transmitting means joining said motor and said power shaft, a motor driven speed reduction device, power transmitting means joining said device and a shaft to operate said cams, a control cam, a hydraulic cylinder, a piston actuated structure adapted to support said movable boards, a valve control on said cylinder and means actuated by said control cam to actuate said valve control to raise and/or lower said structure. 5 10

STANLEY S. MILLEN.
